(57) CLAIM

The ornamental design for an instrument panel for an automobile, as shown and described.

DESCRIPTION

FIG. 1 is a front elevational view of an instrument panel for an automobile in accordance with my new design;

FIG. 2 is a top plan view of the instrument panel in accordance with my new design of FIG. 1;

FIG. 3 is a bottom plan view of the instrument panel in accordance with my new design of FIGS. 1 and 2;

FIG. 4 is a right side elevational view of the instrument panel in accordance with my new design of FIGS. 1 to 3;

FIG. 5 is a left side elevational view of the instrument panel in accordance with my new design of FIGS. 1 to 4;

FIG. 6 is a front, left side perspective view of the instrument panel in accordance with my new design of FIGS. 1 to 5; and,

FIG. 7 is a front, right perspective view of the instrument panel in accordance with my new design of FIGS. 1 to 6.

The rear view and rear surfaces of the instrument panel forms no part of the claimed design. The instrument panel is configured to be mounted to an automobile. The rear view, and rear surfaces, visible in FIGS. 1 to 7 of the instrument panel, form no part of the claimed design since the mounting structure and support structure are hidden when the instrument panel is mounted to the automobile.

A second embodiment of our new design is identical to the first embodiment. The second embodiment of our new design includes the mirror image of the instrument panel shown in FIGS. 1 to 7.
